(57) **CLAIM**

The ornamental design for a control and indicator panel for vehicles, as shown and described.

DESCRIPTION

FIG. 1 is a top, front and right side perspective view of a control and indicator panel for vehicles according to our new design;

FIG. 2 is a top, front and left side perspective view thereof;

FIG. 3 is a left side view thereof;

FIG. 4 is a right side view thereof;

FIG. 5 is a front view thereof;

FIG. 6 is a rear view thereof; and,

FIG. 7 is a top view thereof.

The features shown in broken lines depict portions of the control and indicator panel for vehicles that form no part of the claimed design.
